(57) **CLAIM**

The ornamental design for a barbecue implement with inlay grip, as shown and described.

DESCRIPTION

FIG. 1 is a reduced perspective view of a barbecue implement with inlay grip showing my new design;

FIG. 2 is a front elevational view thereof, the rear elevation view being a mirror image thereof;

FIG. 3 is a side view thereof, the opposite side view being a mirror image thereof;

FIG. 4 is a bottom view thereof; and,

FIG. 5 is a top plan view thereof.

The broken lines are for illustrative purposes only and form no part of the claimed design.
